[57] CLAIM

The ornamental design for a power tool reaction brace, as shown.

DESCRIPTION

FIG. 1 is a right side elevational view of the power tool reaction brace showing my new design with the power tool being shown in broken lines for illustrative purposes only;

FIG. 2 is a rear elevational view thereof;

FIG. 3 is a top plan view thereof;

FIG. 4 is a left side elevational view thereof;

FIG. 5 is a front elevational view thereof;

FIG. 6 is a bottom plan view thereof.

The purpose of the claimed article is to brace an operator's arm and hand while operating a power tool; the upstanding portion fitting the contours of the operator's arm and the portion perpendicular to that supporting the operator's hand.

FIG. 3

FIG. 2

FIG. 1
